UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A BATHING SUIT.

Application filed December 10, 1926. Serial No. 20,005. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Bathing Suit, of which the following is a specification, reference being had to the accompanying drawing, forming part thereof, wherein the design is distinguished by a flared effect to the upper section of the garment and by an ornamental arrangement of borders on the upper and lower sections, one of the borders merging

into a flower formation agreeing with the flower formations distributed over the body of the garment.

Figure 1 is a perspective view of a bathing suit, showing my new design, the same being illustrated on a figure.

Figure 2 is a three-fourths rear perspective view of the bathing suit shown in Figure 1.

I claim:

The ornamental design for a bathing suit, substantially as shown and described.

TAUBE DAVIS.
